UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed February 13, 1924. Serial No. 692,512.

To all whom it may concern:

Be it known that I, MELVIN L. STONE, a citizen of the United States, and a resident of Lawrence, in the county of Essex and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms whereby the operative condition of the loom is changed from time to time.

15 In that type of feeler mechanisms for looms wherein the feeler is given a movement longitudinally of the shuttle to change the operative condition of the loom, as for instance, replenishment of filling, it happens 20 at times that the forward impact of the working supply of filling in the shuttle will cause the feeler to jump and fail to be held by the filling from its "side swipe movement." This is particularly observable in 25 that type of feeler mechanisms wherein the feeler is mounted to enter the shuttle in a direction inclined to the longitudinal axis thereof, although it will happen with other types of feelers.

30 One of the principal objects of the invention is to provide a feeler mechanism of the side swipe type wherein the feeler is locked against movement longitudinally of the shuttle when a working supply of filling is 35 present on a detecting beat, and is freed to partake of its side swipe movement when the filling has approached a degree of substantial exhaustion.

In the feeler mechanism shown, described 40 and claimed in the Edward S. Stimpson Patent, No. 1,309,226, July 8, 1919, the feeler is given its side swipe movement by the frontward pressure upon the feeler on a detecting beat, and the present invention is, 45 in the present instance, shown and described in connection with such type of feeler mechanism, wherein its advantages are readily observable.

In accordance with the present invention, 50 the feeler has mounted thereon a locking member which normally operates to prevent side swipe movement of the feeler when a working supply of filling is present in the shuttle on a detecting beat, and when the 55 filling has approached a degree of deple-

tion approximating substantial exhaustion, the locking member is moved on and relative to the feeler to unlock the feeler and free it to its side swipe movement when the filling is substantially exhausted. 60

In the drawings:

Fig. 1 is a perspective view showing a feeler mechanism provided with the present invention, only such parts of the loom being shown as are desirable in making clear 65 the construction and mode of operation of the feeler mechanism;

Fig. 2 is an enlarged side elevation of the feeler mechanism, showing the position of parts when a working supply of filling is 70 present in the shuttle on a detecting beat;

Fig. 3 is a view similar to that of Fig. 2 with the parts in the position they occupy when the locking member is moved into unlocking position by a predetermined depletion 75 of the filling in the shuttle;

Fig. 4 is a detached perspective view of the locking member; and

Fig. 5 is a cross-section on the line 5—5 of Fig. 2. 80

The feeler mechanism as herein shown is associated with means for effecting a replenishment of filling when the feeler detects substantial exhaustion on a detecting beat, but the replenishing mechanism itself 85 is not herein illustrated because the details thereof form no essential part of the present invention and are now well known.

Extending from the loom frame is the projection portion 1 which may constitute 90 a part of or be secured to the shipper stand. The part 1 is provided, as shown, with a slot 2 through which extends a bolt 3 also passing through a slot 4 in a feeler stand supporting bracket 5, the parts being arranged so that the feeler mechanism may be 95 conveniently adjusted in feeling position. The bracket 5 has a feeler stand supporting portion 6 to which is adjustably secured the feeler stand 7 by means of a bolt 8 passing 100 through a slot 9 in the feeler stand.

The feeler stand is provided with a front and rear bearing for the feeler and in the present instance the feeler stand 7 has a rear bearing 10 projecting upwardly therefrom and provided with a slot 11. The bearing 10 is provided with a guideway for a slide 12 which is also provided with a slot portion 13 through which the feeler 14 extends. The slide 12 is mounted in the rear 110

bearing for lateral movement therein and is connected at 15 to a transmitter 16 which constitutes a part of the train of mechanism for effecting replenishment of filling when 5 the feeler is given its side swipe movement.

The front portion of the feeler stand has a bracket 17 which has mounted therein the swivel bearing 18 through which extends the forwardly projecting stem 19 of the 10 feeler, and between the swivel bearing 18 and a collar 20 on the feeler is interposed a spring 21 which normally acts to move the feeler to its rearward feeling position. The parts so far described and as shown may 15 be of substantially the same construction and mode of operation as the similar parts in the Stimpson patent hereinbefore mentioned.

Overlying the rear bearing 10 and confining the slide 12 in its guideway is a cap plate 22 which may be conveniently secured to the rear bearing by the screws 23. The cap plate 22, in the present instance, is extended upwardly at 24, Fig. 5, to provide a space 25 for movement of the locking member on 20 and relative to the feeler.

The feeler 12 has mounted thereon the locking member 26, which, as shown, is connected to the feeler conveniently at the side thereof for movement on and relative to the 30 feeler. In the present instance, the locking member 26 is provided with the inclined slots 27 through which extend the pins 28, the construction being such that the locking member assumes a locking position relative 35 to the feeler to cooperate with a locking part to prevent movement of the feeler in a direction longitudinally of the shuttle when a working supply is present on a detecting beat. Ordinarily the weight of the locking 40 member 26 will be sufficient to cause the locking member to assume its lowered or locking position, but in some cases it may be desirable to provide additional means to this end, such, for instance, as the spring 29 having a 45 portion 30 overlying the locking member and appropriately secured to the feeler, as, for instance, by the screw 31.

The rear bearing 10, in the present instance, is provided with a notch 32 with 50 which the locking member 26 engages when the locking member is in locking position, and if desired the slide 12 may also be provided with a similar notch, as indicated in Fig. 5, which registers with the locking notch 55 32 when the feeler is in rearward feeling position and locked from its side swipe movement by the locking member.

The present invention contemplates that when the shuttle contains a working supply 60 of filling on detecting beats that the locking member will be engaged with the locking part or notch 32 in the rear bearing of the feeler stand and also it may be with the similar locking notch in the slide 12 to there- 65 by restrain the feeler from premature side

swipe movement, and when the filling has been depleted to an extent approaching substantial exhaustion, it is the purpose of the present invention to cause the locking member to be moved on and relative to the feeler 70 to position the locking member in unlocking relation with the locking part or notch 32.

Mounted on the feeler 12 is the arm 33 which extends rearwardly through the rear end 34 of the feeler and is provided with a 75 filling penetrating point 35. The arm 33 extends through a bearing 36 mounted on the feeler, and is provided with a shoulder or abutment 37 which bears upon the rear turned end portion 38 of the locking member. In the present instance the end 38 of the locking member is provided with a slot 39 through which the front end portion of the arm 33 extends and the abutment 37 is 80 shown as formed by a nut threaded on the arm 33 for adjustment. Also adjustably threaded on the arm 33 is the stop 40 which acts as a limiting means for determining the rearward position of the penetrating point 35 when the locking member is in locking 85 position, as indicated in Fig. 2.

The lay 41 carries the usual shuttle box 42 to receive the shuttle 43 wherein is mounted the filling carrier or bobbin 44. The front wall of the shuttle is provided 90 with an opening 45, and similarly the front wall of the shuttle box is provided with an opening 46, said openings being in registered relation when the shuttle is properly boxed to permit the feeler 14 to enter the shuttle 100 and feel for the filling.

In cases where the feeler is of the inclined type, as shown, the rear end of the feeler is given a normal lateral movement by the 105 frontward pressure of the filling on each detecting beat, and the notch 32 is made of sufficient size to permit such normal movement, and when the filling is depleted to a degree approaching substantial exhaustion, the locking member 26 is moved on and relative to the feeler by engagement of the point 35 of the arm 33 with the more dense surface of the filling carrier or bobbin on a detecting beat, the result being that movement of the locking member relative to the 110 feeler causes the former to be moved frontwardly and upwardly relative to the feeler, in the present instance, to place the locking member in unlocking position, whereupon the feeler is freed to its side swipe movement when the filling becomes substantially exhausted.

From the construction and description it will be apparent that when a working supply of filling is present in the shuttle on a 115 detecting beat and the locking member is in locking position, the penetrating point 35 of the arm 33 will sink into the filling and the locking member will remain in locking position. When, however, the filling has 120

- approached substantial exhaustion and only a few strands of the filling remain upon the filling carrier or bobbin, the point 35 of the arm 33 will engage the more dense surface 5 of the filling carrier or bobbin, as indicated in Fig. 3, and will be moved forwardly relative to the feeler, thereby causing the locking member 26 to be moved on and relative to the feeler into an unlocking position, Fig. 3. The unlocking position of the locking member, in the present instance, is effected by the arm 33 and the inclined slots 27 on the locking member cooperating with the pins 28 which connect it to the feeler. The construction is simple, effective and peculiarly adaptable to the side swipe type of feeler, and applicant believes himself to be the first in the art to provide a locking member mounted on the feeler for movement relative thereto into an unlocking position when the filling in the shuttle has been depleted to a predetermined degree, and while the construction shown and described is a good practical form of the invention, it is to be understood that the invention may be carried into effect through the medium of different details within the true scope of the invention as pointed out by the claims.
- 30 What is claimed is:
1. In a feeler mechanism for looms, the combination of a feeler, a feeler lock mounted on the feeler, a stationary part which cooperates with the feeler lock to prevent the feeler calling for a change of filling prematurely, and a penetrating lock tripping part which acts upon the feeler lock to move it on the feeler from locking engagement with the said stationary part when the penetrating lock tripping part contacts with the dense surface of the bobbin on a detecting beat.
  2. In a feeler mechanism for looms, the combination of a feeler supported for normal lateral movement by the forward pressure of a working supply of filling in the shuttle on a detecting beat and an abnormal lateral movement along the filling carrier when the filling is substantially exhausted on a detecting beat, a feeler locking member which is mounted on the feeler and permits normal lateral but prevents abnormal lateral movement of the feeler by the forward pressure on a detecting beat until the filling reaches a condition approaching substantial exhaustion and which is then moved on and relative to the feeler into an unlocking position to permit the abnormal lateral movement of the feeler.
  3. In a feeler mechanism for looms, the combination of a feeler, a locking member mounted on the feeler, a stationary cooperating locking part with which said locking member is normally engaged during weaving with a working supply of filling to prevent movement of said locking member and the feeler on which it is mounted in a direction longitudinally of the shuttle until the filling is substantially exhausted, and means for directing the movement of the locking member out of engagement with the cooperating stationary part when the locking member is moved on the feeler relative thereto on a detecting beat.
  4. In a feeler mechanism for looms, the combination of a feeler mounted to enter the shuttle in a direction inclined to the longitudinal axis thereof, a locking member mounted on the feeler for movement with and relative thereto a fixed locking part with which the locking member is normally engaged so long as a working supply of filling is in the shuttle on detecting beats, and means cooperating with the filling carrier when the filling has approached a condition near to substantial exhaustion on a detecting beat for moving the locking member on the feeler relative to the cooperating stationary locking part and out of engagement therewith to permit the feeler to side swipe.
  5. In a feeler mechanism for looms, the combination of a feeler, a locking member mounted on the feeler, a fixed cooperating part on the feeler stand with which the locking member is normally engaged and with relation to which it is moved forwardly on detecting beats when a working supply of filling is in the shuttle, and a filling penetrating member for moving the locking member from engagement with said fixed part when it meets the more dense surface of the filling carrier on a detecting beat.
  6. In a feeler mechanism for looms, the combination of a feeler that is mounted to be displaced laterally along the filling carrier by the forward pressure to effect replenishment of filling, a locking member movable on and relative to the feeler into and out of locking position, a fixed part on the feeler stand cooperating with the locking member to lock the feeler from lateral movement to call for a change of filling when a working supply is in the shuttle on a detecting beat, a penetrating lock controller which is adapted to engage the more dense surface of the filling carrier when, on a detecting beat, the filling is depleted to a predetermined extent and be moved forwardly thereby, and means for transmitting such movement of the controller to the locking member to disengage it from the cooperating fixed part that the feeler may be freed to call for a change of filling when that in the shuttle is substantially exhausted.
  7. In a feeler mechanism for looms, the combination of a feeler mounted for movement in a direction longitudinally of the shuttle to effect replenishment of filling, a

- locking member, connections between the feeler and locking member including an inclined slot on one and a pin on the other engaging said inclined slot constructed and 5 arranged that movement of one relative to the other will effect movement of the locking member into or out of locking position, and means rendered effective when the filling is nearly exhausted on a detecting beat to 10 move relatively the locking member and feeler to unlock the latter and free it to call for replenishment of filling when that in the shuttle is substantially exhausted on a detecting beat.
- 15 8. In a feeler mechanism for looms, the combination of a feeler, a locking member mounted on the feeler, a fixed cooperating locking part normally engaged by the locking member to restrain filling replenishing movement of the feeler as the latter is moved frontwardly by a working supply of filling on detecting beats, and a filling penetrating member for moving the locking member out of engagement with the fixed 20 25 locking part when the penetrating member is moved by the more dense surface of the filling carrier.

9. In a feeler mechanism for looms, the combination of an inclined feeler, a locking member mounted on and movable relatively to the feeler, a locking notch normally engaged by the locking member to hold the feeler from prematurely calling for a change of filling, a filling penetrating member for moving the locking member on and relatively to the feeler out of engagement with the locking notch when the penetrating member is moved relative to the feeler by engagement with the more dense surface of the filling carrier. 30 35 40

10. In a feeler mechanism for looms, the combination of an inclined feeler, a locking member mounted on and movable relatively to the feeler, a locking notch normally engaged by the locking member to hold the feeler from prematurely calling for a change of filling, a filling penetrating member for moving the locking member on and relatively to the feeler, and means for directing the movement of the locking member to carry it. 45 50

In testimony whereof, I have signed my name to this specification.

MELVIN L. STONE.
